UNITED STATES PATENT OFFICE

WADE H. WINEMAN, OF MICHIGAN CITY, INDIANA, ASSIGNOR TO SULLIVAN MACHINERY COMPANY, A CORPORATION OF MASSACHUSETTS

PUNCHING MECHANISM

Application filed April 14, 1927. Serial No. 183,854.

This invention pertains to punching mechanisms and more particularly to pneumatic punching mechanisms for opening or pinning out the holes in hollow rock drill steels.

5 An object of this invention is to provide an improved punching mechanism. Another object of this invention is to provide an improved pneumatic punching mechanism for opening the holes in hollow drill steels 10 wherein the pinning out tool is hammered by successive blows into the steel and retracted from the steel by but a single blow. Another object is to provide an improved pneumatic punching mechanism wherein the 15 pinning out tool is hammered into and out of the steel. Still another object of this invention is to provide an improved punching mechanism wherein a hammer mechanism is provided for hammering the punch into the 20 steel and a separate hammering mechanism for hammering the punch out of the steel. Yet another object of this invention is to provide an improved pneumatic clamping mechanism or vise for holding the drill steel in 25 position during the punching operation. Another object is to provide an improved pedestal type punch wherein the punching mechanism and vise are mounted on a common support in an improved manner. An 30 other object is to produce a clamping mechanism which is quick in operation both in gripping and releasing the steel and which is of exceedingly simple and rugged structure. These and other objects and advantages of this invention will, however, subsequently more fully appear.

In the accompanying drawings I have shown for purposes of illustration one form 40 which the invention may assume in practice.

In these drawings,—

Fig. 1 is a side elevation of the improved 45 punching mechanism.

Fig. 2 is a plan view of the punching 50 mechanism shown in Fig. 1.

Fig. 3 is a fragmentary end elevational 55 view of the punching mechanism shown in Fig. 1, the view looking toward the clamping mechanism.

59 Fig. 4 is an enlarged central longitudinally

extending vertical sectional view taken on line 4—4 of Fig. 2.

Fig. 5 is a detail rear end elevation of the improved hammering mechanism and guiding means therefor, with parts broken away. 55

Fig. 6 is a detail sectional view taken on line 6—6 of Fig. 1.

In this illustrative embodiment of the invention there is shown a punching mechanism generally designated 1 generally comprising a fluid actuated hammering mechanism 2 and fluid actuated clamping mechanism or vise 3, the hammering mechanism and vise both being mounted on a common 60 hollow base or pedestal 4.

The hammering mechanism 2, as shown in the drawings, specifically comprises a bracket 5 secured by bolts 6 to a laterally projecting arm 7 herein formed integral with the pedestal 4. The bracket 5 has a longitudinally extending guideway 8, herein a T-shaped groove which slidably receives a T-shaped guide member 9, herein preferably formed integral with a cradle or carriage member 10. The carriage member 10 is here- 65 in preferably in the form of a cylinder having a longitudinally extending bore 11 in which a hammer piston 12 is reciprocably mounted. The carriage member 10 has ex- 70 tending upwardly from both ends thereof brackets 13 and 14 having respectively slots 15 and 16. Slidably mounted on the carriage member 10 is a pneumatic piston type ham- 75 mer motor generally designated 17, herein preferably of a standard type and comprising a cylinder 18 within which a hammer piston 19 of usual form is reciprocably mounted.

Suitably rigidly secured to the rear end of the cylinder 18 is a combined cylinder head and valve chest or housing 20 having a cylindrical exterior surface 21 disposed in sliding contact with an arcuate surface 22 formed on the cradle member 10, thereby forming a 80 guide for the motor 17. Arranged within the valve chest 20 is a usual automatic fluid distribution valve 23 which is adapted to control the supply of motive fluid flowing through a passage 24 to the motor cylinder 18 and the exhaust of fluid from the motor cylinder through a usual exhaust passage 85

100

25. The valve chest or housing 20 is provided with a cylindrical portion which slidably fits a bore 26 formed within a cap member 27, the member 27 being slidably mounted on the 5 valve housing. A boss 28 projects rearwardly from the cap 27 and is disposed within the slot 15 in the bracket 13. To limit movement of the valve housing 20 within the cap 27 an air inlet connection 29 is provided 10 preferably secured to the housing 20 and projecting laterally through an elongated slot 30 formed in the cap 27. Suitably secured to the cap member 27 is a valve 31 slidably mounted in a bore 32 formed in the valve 15 housing 20. From the foregoing description it will be evident that when the cap member 27 is moved axially relative to the hammer mechanism 17 the valve 31 will open communication between the fluid supply connection 29 and the supply passage 24 and consequently fluid is admitted to the cylinder 18, thereby effecting reciprocation of the hammer piston 19. Reciprocably mounted within the forward end of the hammer mechanism 17 is an elongated collared pinning out 20 tool or punch 33 having loosely mounted thereon a collar or washer 34. This punch 33 extends forwardly through the slot 16 in the bracket 14. The shank portion of the 25 punch 33 extends rearwardly within the motor cylinder 18 in position to receive impact blows delivered thereon by the hammer piston 19.

Referring more particularly to Fig. 4 it 30 will be observed that the hammer piston 12 is of the two spool type and is adapted when disposed in the rear end of the cylinder bore 11 to have its annular groove portion adjacent a port 35 with which the motor exhaust 35 passage 25 communicates. A series of flutes or grooves 36 formed on the periphery of the rear spool of the piston 12 connects the groove with the rear end of the piston. During running of the hammer motor 17 exhaust 40 fluid flows through the port 25, port 35, through the groove in the piston 12 and through the flutes 36 to the rear end of the cylinder bore 11 and consequently the fluid acting on the rear pressure area of the piston 45 12 moves the latter to its extreme forward 50 position.

The hammering mechanism 17 and the cradle member 10 are adapted to be fed manually longitudinally within the guideway 8 55 and this feeding mechanism comprises a screw 37 threadedly secured within the boss 28 on the cap member 27. Threadedly connected to the screw 37 is an adjustable stop nut 38. A substantially flat link member 39 has a laterally bent portion 40 provided with an opening through which the screw 37 extends. Interposed between the stop nut 38 and the bent portion 40 of the link member 39 and encircling the screw 37 is a coiled spring 41 and 60 this spring normally tends to maintain the 65

portion 40 and the cap member 27 in engagement and to hold the collar on the tool 33 and the washer 34 away from the bracket 14 on the carriage. This link 39 extends forwardly of the mechanism and is pivotally connected at 42 to a lever 43, the latter in turn being pivotally connected at 44 to an arm 45 on the base 4. Carried on the forward end of the link 39 is a depending arm 46 adapted to engage upon movement of the link a valve stem 47 (see Fig. 6) of an end seating valve 48 engageable with a valve seat 49 formed within a valve housing 50, herein preferably formed integral with the carriage member 10 at the forward end thereof. The valve housing 50 has stepped bores 51 and 52, the juncture of which provides the valve seat 49. The stem 47 is provided with a reduced portion 53 and is adapted to control in atmospheric exhaust port 54 communicating with the bore 52. As shown a passage 55 leads from the bore 52 to the cylinder bore 11, while an air inlet passage 56 communicates with the bore 51. When the valve 48 is seated the cylinder bore 11 at the forward end of the piston 12 is vented to atmosphere through passage 55 and the port 54. The passage 56 is connected through a suitable pipe connection 57 to the inlet supply connection 29 for the hammer motor 17, while the connections 29 and 57 are in turn connected through a pipe connection 58 to a pressure fluid supply line 59.

In accordance with this illustrative embodiment of the invention the pneumatic clamping mechanism or vise specifically comprises a diaphragm chamber 60 formed within the pedestal 4 at the upper end thereof and extending completely across this diaphragm chamber is a horizontal flexible diaphragm 61 having its outer edge clamped by means of a plate 62 and bolts 63 to the upper portion of the pedestal. As shown in Fig. 4 the lower surface of the diaphragm 61 engages a horizontal flat disc shaped member or plate 64 having threadedly connected thereto at 65 a vertically movable plunger 66, the latter being guided within a bore 67 formed within the pedestal. The lower end of the plunger 66 contacts with one arm of a lever 68 pivoted at 69 on a horizontal axis on the arm 45. The other arm of the lever 68 contacts with the lower end of a movable vise member or jaw 71 guided for vertical movement within a bore 72 formed within an upstanding U-shaped portion 73 carried by the arm 45. As shown in Fig. 3 the U-shaped portion of the frame is open at one side to permit the lateral insertion of a steel between the vise jaws or the removal of a steel from the jaws. Disposed within a chamber formed within the arm 45 and engaging the upper surface thereof is a coiled spring 74 surrounding the movable vise member 71 and engaging a transverse pin 75 carried by the vise member. The spring 74 constantly tends to force the vise 100 105 110 115 120 125 130 135 140 145 150 155 160 165 170 175 180 185 190 195 200 205 210 215 220 225 230 235 240 245 250 255 260 265 270 275 280 285 jaw 71 downwardly into its released position. The movable vise member 71 has formed on the upper surface thereof a V-shaped notch 76 which is adapted to receive and position a usual hollow rock drill steel 77. The upper stationary vise jaw comprises a detachable plate or abutment 78 rigidly held in place by means of a bolt 79. Pressure fluid is adapted to be supplied to the diaphragm chamber 60 from the supply connection 59 through a pipe connection 80 under the control of a usual valve 81. The valve 81 is adapted to admit fluid to the diaphragm chamber and to cut off the flow of fluid to the chamber and vent the latter to atmosphere.

In the operation of the improved punching mechanism, assuming the parts to be in their withdrawn position as shown in Figs. 1 and 4, the operator will first place the steel 77 within the V-shaped notch 76 in the lower vise jaw and upon suitable manipulation of the valve 81 pressure fluid will be admitted to the diaphragm chamber 60, the fluid acting on the diaphragm 61 moving the plunger 66 downwardly. The lever 68 then swings about its pivot and consequently the lower vise jaw 71 is moved upwardly, rigidly clamping the hollow drill steel 77 in position against the top plate 78. The operator will then grasp the lever 43 and move the link 39 forwardly thereby moving the carriage member 10 and the hammer mechanism 17 thereon forwardly within the guide way 8 to cause engagement of the punch 33 with the drill steel 77. Upon engagement of the punch 33 with the steel 77, the collar on the punch prevents further forward movement of the hammer mechanism 17 and consequently as the operator continues to pull the lever 43 the cradle member 10 and consequently the cap member 27 move forwardly relative to the hammer mechanism 17 and also to cause the valve 31 to move within the bore 32 thereby permitting flow of pressure fluid to the motor cylinder 18. This will cause the piston 19 to be rapidly reciprocated to impart a series of impact blows to the punch 33 and exhaust fluid from the motor cylinder 18 then flows through the ports 25 and 35, through the groove in the piston 12, and through the flutes 36 to the rear end of the cylinder bore 11. Due to the fact that the motor exhaust pressure at all times is far above atmospheric pressure the piston 12 will be forced to the front end of the cylinder bore 11. However, the normal exhaust from the motor 17 will take place through the port 25 and port 35 which also communicates with the atmosphere. As the punch 33 is hammered into the drill steel, the link 39 and the lever 43 are grasped by the operator and cause movement of both the hammer mechanism 17 and the carriage member 10 and consequently the punch 33 is fed forwardly as the hole in the drill steel is opened. During withdrawal of the punch the operator

will swing the lever 43 rearwardly, consequently moving the link 39 rearwardly and due to compression of the spring 41 there will be substantial lost motion between the bent portion 40 of the link and the nut 38, the hammer mechanism and carriage member therefore remaining stationary at that time while the cap member 27 and valve 31 carried thereby move rearwardly, consequently cutting off the supply of pressure fluid flowing to the motor 17. The arm 46 on the link 39 will, however, move rearwardly with the link and will engage the valve stem 47. Upon engagement of the arm 46 with the stem 47 the valve 48 will be unseated, thereby allowing communication between the bore 51 and the passage 55 whereupon a sudden flow of pressure fluid from the supply connection 57 to the cylinder bore 11 by way of the passage 55 will cause the hammer piston 12 to be driven suddenly rearwardly to impinge with great force against the rear end wall of the cylinder bore. During this time the collar on the punch 33 and the washer 34 will be engaged with the upstanding lug 14 and the impact action of the hammer 12 will be transmitted through the carriage member 10 and the lug 14 to the punch 33 to cause withdrawal thereof from the steel. After the punch 33 is withdrawn from the drill steel the valve 81 is again manipulated and the fluid in the diaphragm chamber 60 is exhausted to atmosphere. The spring 74 then forces the lower vise jaw 71 downwardly into its released position thereby permitting the operator to remove the steel from the vise. These and other operations and uses of the improved punching mechanism will be clearly apparent to those skilled in this art.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a punching mechanism, a guideway, a carriage slidable on said guideway, a hammer mechanism movably mounted on said carriage, and means for manually feeding said hammer mechanism and carriage relative to said guideway comprising an actuating member extending longitudinally of the carriage and having a laterally bent portion normally engaging said carriage, an abutment carried by said hammer mechanism, and a coiled spring interposed between said bent portion and said abutment to form a resilient connection between said actuating member and said hammer mechanism and between said carriage and said hammer mechanism.

2. In a punching mechanism, a guideway,

a carriage slidable on said guideway, a hammer mechanism including a cylinder and piston movably mounted on said carriage, a collared pinning tool mounted in and actuated by said hammer mechanism, said carriage having upstanding brackets supporting said hammer mechanism, a washer loosely mounted on said pinning tool and interposed between the collar thereon and the adjacent one 10 of said brackets, and means for moving said carriage relative to said hammer mechanism to cause said adjacent bracket to transmit retracting force to the collar on said pinning tool.

15 3. In a punching mechanism, a frame presenting a guideway, a carriage slidably mounted on said guideway, a hammer mechanism movably mounted on said carriage, and means for manually feeding said hammer mechanism and carriage relative to said guideway comprising a lever pivoted on said frame, and an actuating rod pivotally connected to said lever having an operative connection with said carriage and an independent direct resilient connection between said actuating rod and said hammer mechanism.

4. In a punching mechanism, a frame presenting a guideway, a carriage slidable on said guideway, a fluid actuated hammer mechanism movably mounted on said carriage, a fluid actuated vise on said frame for clamping a steel in position to be acted on by said hammer mechanism, and means for manually feeding said hammer mechanism and carriage relative to said guideway comprising a lever pivotally connected to said frame, and an actuating rod pivotally connected to said lever having an operative connection with said carriage and an independent direct resilient connection between said actuating rod and said hammer mechanism.

45 5. In a punching mechanism, a frame presenting a guideway, a carriage slidable on said guideway and having a hammer mechanism carried thereby, a second hammer mechanism movably mounted on said carriage, and means including a lever resiliently connected to said second mentioned hammer mechanism for feeding the latter forwardly 50 and for retracting said second mentioned hammer mechanism to effect operation of said first mentioned hammer mechanism.

6. In a punching mechanism, a frame presenting a guideway, a carriage slidable on said guideway, a hammer mechanism carried by said carriage, a second hammer mechanism movably mounted on said carriage, and manually operable means including a lever 55 pivotally connected to said frame and resiliently connected to said second mentioned hammer mechanism for moving the latter forwardly to effect a pinning out operation on a drill steel and for retracting said second 60 mentioned hammer mechanism to effect op-

eration of said first mentioned hammer mechanism.

7. In a punching mechanism, a guideway, a carriage slidable on said guideway, said carriage having an upstanding slotted bracket thereon, a hammer mechanism including a cylinder and piston movably mounted on said carriage and having a collared pinning tool extending through the slot in said bracket, and a washer loosely mounted on said pinning tool and interposed between the collar thereon and said bracket. 75

8. In a punching mechanism, a guideway, a carriage slidable on said guideway, said carriage having an upstanding slotted bracket thereon, a hammer mechanism including a cylinder and piston movably mounted on said carriage and having a collared pinning tool extending through the slot in said bracket, a washer loosely mounted on said pinning tool and interposed between the collar thereon and said bracket, and means for moving said carriage relative to said hammer mechanism to cause said bracket to engage said washer and transmit a retracting force to the 90 collar on said pinning tool. 95

9. In a punching mechanism, a guideway, a carriage slidable on said guideway, said carriage having an upstanding slotted bracket thereon, a hammer mechanism movably mounted on said carriage and having a collared pinning tool extending through the slot in said bracket, a washer loosely mounted on said pinning tool and interposed between the collar thereon and said bracket, means for moving said carriage relative to said hammer mechanism to cause said bracket to engage said washer and transmit a retracting force to the collar on said pinning tool, and means for imparting a blow to said carriage to effect movement of said pinning tool in one direction. 100 105

10. In a punching mechanism, a guideway, a carriage slidable on said guideway, said carriage having an upstanding slotted bracket thereon, a hammer mechanism including a cylinder and piston movably mounted on said carriage and having a collared pinning tool extending through the slot in said bracket, and a washer loosely mounted on said pinning tool and interposed between the collar thereon and said bracket, and resilient means forming a connection between said hammer mechanism and said carriage normally maintaining said bracket out of contact with said washer and collar. 110 115

11. In a punching mechanism, a frame presenting a guideway, a carriage slidably mounted in said guideway, a unitary pressure fluid operated hammer mechanism mounted on said carriage so as to permit a limited longitudinal movement relative to said carriage, an actuating member adapted to engage said carriage for moving said carriage and hammer mechanism along said 120 125 130

guideway, and resilient means for normally holding said hammer mechanism in one of its extreme positions relative to said carriage, said resilient means also forming a resilient connection between said actuating member and hammer mechanism.

12. In a punching mechanism, a frame presenting a guideway, a carriage slidably mounted in said guideway, a unitary pressure fluid operated hammer mechanism slidably mounted on said carriage, a punch carried by and actuated by said hammer mechanism, said punch having a collar thereon, an abutment fixed to said carriage adapted to act upon said collar to withdraw the punch from its work, resilient means forming a connection between said carriage and hammer mechanism normally maintaining said abutment away from said collar, and means for manually feeding said carriage and hammer mechanism relatively to the work.

In testimony whereof I affix my signature.
WADE H. WINEMAN.
